UNITED STATES PATENT OFFICE

163,780

COVERED RECEPTACLE

Franz Wagner, Chicago, Ill., assignor to Nesco, Inc., Milwaukee, Wis., a corporation of New Jersey

Application October 25, 1950, Serial No. 12,718

Term of patent 14 years

(Cl. D58—22)

To all whom it may concern:

Be it known that I, Franz Wagner, a citizen of the United States, residing at Chicago, State of Illinois, have invented a new, original, and ornamental Design for a Covered Receptacle, of which the following is a specification, reference being had to the accompanying drawing, forming a part hereof.

I claim:

The ornamental design for a covered receptacle, as shown.

FRANZ WAGNER.
